HAIR CURLER

Tessie J. Heaton, Newton, Mass.

Application June 21, 1948, Serial No. 34,308

5 Claims. (Cl. 132—33)

1

This invention relates to hair curlers and more particularly to those which wind tresses of hair into uniform pin curls beginning from the end of the hair nearer to the scalp.

The most common type of present curlers do not wind curls in uniform ringlets. Usually the curl is wound from the free end towards the scalp and therefore cannot pick up the shorter strands of hair. The curlers that work from the scalp outward do not form curls of parallel strands due to the lack of proper means for feeding the hair on to the curling mechanism.

A primary object of my invention is to produce a pin curler that winds the tress from the scalp outward, smoothing, adjusting and confining it into evenly and uniformly wound curls.

In accordance with my invention there is produced a pin curler that is simple of construction and operation. It produces a better curl due to its guiding, feeding and hair straightening features. Uniform curls are produced. All ringlets are tight. All strands of hair, short and long, are included in the curl. All strands are substantially parallel producing a more pleasing result. The device is rugged, fool proof, and inexpensive to manufacture.

Further objects of the invention will hereinafter appear from the following description of a preferred embodiment illustrative of the invention and shown in the accompanying drawings in which

Fig. 1 is a perspective view of my device before operation.

Fig. 2 is a side elevation.

Fig. 3 is an end elevation.

This hair curler consists of a spindle around which revolves a tubular sleeve or member. To this revolving member is attached an elongated spiral through which the strands of hair are evenly drawn and wound on the spindle forming a superior curl.

Referring to the drawings, the device therein shown comprises a stationary cylindrical spindle 1 on one end of which there is a narrow slot 2, the bottom of the slot ending at point 3. Rotatably engaging with spindle 1, is a tubular member 4 which has a raised portion 5 at one end to assist in the rotation. Attached to the tubular member 4 is an extension arm 7 which extends over the spindle 1 and parallel to it, separated from it by the space 14. When substantially over the bottom 3 of the slot 2, the extension arm forms the proximal circle-like convolution 8 of a spiral, with the plane passing through a substantial portion of the convolution 8 being perpendicular

2

to an extended radius of spindle 1. Convolution 8 then extends substantially at right angles into an elongated arm 6 and thence into the distal convolution 9 of the spiral, with the plane passing through a substantial portion of the convolution 9 not being perpendicular to an extended radius of the spindle 1. The center 10 of the opening of the convolution 8 and the center 11 of the opening of the convolution 9 and the end 3 of the slot 10 2 lie substantially on an extended radius of the spindle 1. The spindle 1 is provided with a snug fitting non-rotatable sleeve 12 to form a handle.

In operating the device, a tress of hair adjacent to the scalp and sufficient for one pin curl 15 is introduced into slot 2. It is then wound around arm 6 into the opening 10 of convolution 8, then into opening 11 of convolution 9. This tress is thus held by the arm 6 in a straight line perpendicular to the spindle 1 with all hairs, 20 short and long substantially parallel.

Holding the device inside the hand by the third and fourth fingers, the slotted end 13 of the spindle 1 is held against the scalp, the spindle being perpendicular to the scalp. Turning the 25 tubular member by means of the thumb and the first and second fingers, the straightened tress is fed evenly through the openings 10 and 11 around the spindle 1 into the space 14 provided to receive the curl.

30 The oblique angle of the plane of the opening 11 has sufficient binding effect on the tress to feed it under tension onto the spindle. When the entire tress has been fed through the convolutions of the spiral arm from the scalp to the free end 35 of the hair, the curl is slipped off the spindle and secured by means of any of the usual fastening devices.

It is apparent that the details of the device described may be varied without departing from 40 the nature or principle of my invention and it is my intention not to limit the invention to the particular details set forth but to describe one method of obtaining the desired end so that said end, being once realized, may be accomplished 45 by changes in the construction and arrangements of the several parts, provided that such changes fall within the scope of the appended claims.

Having described the preferred embodiment 50 illustrative of my invention, I claim:

55 1. A pin curler comprising a stationary cylindrical spindle and a tubular rotatable member provided with an elongated spiral guide and tension arm, so constructed and arranged that said tubular member rotates around said spindle at one location only, said spiral arm being

fastened to and extended beyond one end of said member and at right angles to it, the axis of said spiral arm being coincident with an extended radius of said member, the plane described by said axis on rotation being perpendicular to the axis of said cylindrical spindle, said spindle being provided with a transverse guide slot extending from one end, the closed end of said slot ending at and coincident with said radius, said slotted end being adapted to be pressed endwise against the scalp of a person.

2. A pin curler comprising a stationary cylindrical spindle and a tubular rotatable member provided with an elongated spiral guide and tension arm, so constructed and arranged that said tubular member rotates around said spindle at one location only, said spiral arm being fastened to and extended beyond one end of said member and at right angles to it, the axis of said spiral arm being coincident with an extended radius of said member, the plane described by said axis on rotation being perpendicular to the axis of said cylindrical spindle, said spindle being provided with a transverse guide slot extending from one end, the closed end of said slot ending at and coincident with said radius, said member being positioned from said slotted end, said slotted end being adapted to be pressed endwise against the scalp of a person, said slot and spiral arm being adapted to position a tress of hair substantially parallel to said scalp, said slot holding scalp end of tress in place, said spiral arm winding said tress in a coil around the longitudinal sides of said slot, one convolution of said coil being wound on top of the preceding convolution when said tubular member is rotated around said spindle.

3. A pin curler comprising a stationary cylindrical spindle and a tubular rotatable member provided with an elongated spiral guide and tension arm, so constructed and arranged that said tubular member rotates around said spindle at one location only, said spiral arm being fastened to and extended beyond one end of said member and at right angles to it, the axis of said spiral arm being coincident with an extended radius of said member, the plane described by said axis on rotation being perpendicular to the axis of said cylindrical spindle, said spindle being provided with a transverse guide slot extending from one end, the closed end of said slot ending at and coincident with said radius, said slotted end being adapted to be pressed endwise against the scalp of a person, said member being positioned from said slotted end, said spiral having a proximal convolution and a distal convolution, the plane passing through a substantial portion of the proximal convolution being perpendicular to said radius, said slot and spiral arm being adapted to position a tress of hair substantially parallel to said scalp, said slot holding scalp end of tress in place, said spiral arm winding said tress in a coil around the longitudinal sides of said slot, one convolution of said coil being wound on top of the preceding convolution when said member is rotated around said spindle.

4. A pin curler comprising a stationary cylindrical spindle and a tubular rotatable member provided with an elongated spiral guide and tension arm, so constructed and arranged that said tubular member rotates around said spindle, at one location only, said spiral arm being fastened to and extended beyond one end of said member and at right angles to it, the axis

of said spiral arm being coincident with an extended radius of said member, the plane described by said axis on rotation being perpendicular to the axis of said cylindrical spindle, said spindle being provided with a transverse guide slot extending from one end, the closed end of said slot ending at and coincident with said radius, said slotted end being adapted to be pressed endwise against the scalp of a person, said member being positioned from said slotted end, said spiral having a proximal convolution and a distal convolution, the plane passing through a substantial portion of the proximal convolution being perpendicular to said radius, and the plane passing through a substantial portion of the distal convolution not being perpendicular to said radius, said slot and spiral arm being adapted to position a tress of hair substantially parallel to said scalp, said slot holding scalp end of tress in place, said spiral arm winding said tress in a coil around the longitudinal sides of said slot one convolution of said coil being wound on top of the preceding convolution when said member is rotated around said spindle.

5. A pin curler comprising a stationary cylindrical spindle and a tubular rotatable member provided with an elongated spiral guide and tension arm, so constructed and arranged that said tubular member rotates around said spindle at one location only, said spiral arm being fastened to and extended beyond one end of said member and at right angles to it, the axis of said spiral arm being coincident with an extended radius of said member, the plane described by said axis on rotation being perpendicular to the axis of said cylindrical spindle, said spindle being provided with a transverse guide slot extending from one end, the closed end of said slot ending at and coincident with said radius, said slotted end being adapted to be pressed endwise against the scalp of a person, said member being positioned from said slotted end, said spiral having a proximal convolution and a distal convolution, the plane passing through a substantial portion of the proximal convolution being perpendicular to said radius, and the plane passing through a substantial portion of the distal convolution not being perpendicular to said radius, the thickness of said slot and the separation between said spreader arm and said spindle being approximately equal, said slot and spiral arm being adapted to position a tress of hair substantially parallel to said scalp, said slot holding scalp end of tress in place, said spiral arm winding said tress in a coil around the longitudinal sides of said slot one convolution of said coil being wound on top of the preceding convolution when said member is rotated around said spindle.
